UNITED STATES PATENT OFFICE.

GEORGE A. HUMPHREY, OF KALAMAZOO, MICHIGAN, ASSIGNOR TO GENERAL GAS LIGHT COMPANY, OF KALAMAZOO, MICHIGAN.

GAS STOVE.

Application filed March 15, 1926. Serial No. 94,760.

The main object of this invention is to provide a heating unit which is readily adapted for embodiment in gas stoves, fireplaces and the like.

Objects relating to details and economies of the invention will definitely appear from the detailed description to follow. The invention is clearly defined and pointed out in the claims.

10 A structure embodying the features of my invention is clearly illustrated in the accompanying drawings forming a part of this application, in which:

Fig. 1 is a fragmentary vertical section 15 through a structure embodying the features of my invention as adapted to a gas stove or range.

Fig. 2 is a fragmentary horizontal section on a line corresponding to line 2—2 of Fig. 1.

20 Fig. 3 is an inside perspective view of the heater unit casing.

Fig. 4 is an inside view of the face or front plate.

Fig. 5 is a detail section on a line corresponding to line 5—5 of Fig. 2.

Fig. 6 is a front perspective view showing an adaptation of my improved heating unit to a fireplace.

Fig. 7 is a detail section on a line corresponding to line 7—7 of Fig. 6.

Fig. 8 is a detail section on a line corresponding to line 8—8 of Fig. 6.

Referring to the drawing, the embodiment illustrated in Figs. 1 to 5, inclusive, comprises a panel-like support 6 which in the embodiment there illustrated is the back panel or splash wall of a gas stove having a shelf 7 adjacent the top thereof. This panel is provided with an opening 8.

40 On the rear side of the panel and in opposed relation to this opening, I mount a casing comprising a back wall 9 and end walls 10 formed integrally of sheet metal and having out-turned flanges 11 at the forward edges disposed against the rear side of the panel 6.

Within this casing I mount a supporting plate 12, preferably a casting, having openings 13 therein with which the tips 14 of the burner 15 are alined. The supporting plate 50 has a downwardly projecting flange 16 at its front edge, the burner being secured to this flange by means of the screws 17.

The fireback 18 of earthy material is mounted upon this supporting plate and ra-

diating elements 19 are arranged in front of 55 the fireback and in operative relation to the burner tips. The supporting plate has lugs 20 with which the attaching screws 21 engage. A retaining clip 22 engages the top of the fireback supporting it in position. 60

The casing is in the embodiment illustrated secured by means of the bolts 23 arranged through the face or front plate 24 disposed on the front side of the panel 6 around and framing the opening. This frame has a forwardly projecting hood 25 at its upper end and inwardly projecting flanges 26 at the top and sides thereof which project through the opening in the panel, thereby preventing the products of combustion passing from the radiating elements or the casing under the frame and discoloring the face of the panel. This frame also adds greatly to the appearance. In the structure illustrated a grid 27 is provided. 75

The supporting plate is further supported by screws 28 arranged through the frame and back panel and engaging the flange. This provides a very secure mounting for the heating unit. 80

The casing has a top 29 and vent openings 30.

In the embodiment shown in Fig. 6 the panel corresponding to the panel 6 is adapted to fit a frame 34 in a fireplace shown conventionally at 35. The panel may be ornamented as desired, the panel illustrated being ornamented to imitate tile. 85

The structure has the advantage of being readily adapted to fire place openings of different sizes and at the same time has an attractive finished appearance. The structure also has the advantage of being very economical. 90

I have illustrated and described adaptations of my improvements which I have found very practical. I have not attempted to illustrate and describe other embodiments and adaptations as I believe the disclosure made will enable those skilled in the art to 95 embody or adapt my improvements as may be desired. 100

Having thus described my invention what I claim as new and desire to secure by Letters Patent is:

1. A gas heater comprising a panel having an opening therein, a casing comprising sheet metal back and end walls having flanges

- at the front edges thereof disposed against the rear side of said panel at the edges of said opening therein, a supporting plate having a flange at its front end disposed within said casing and secured to the walls thereof, a burner mounted on said supporting plate, radiating elements disposed on said supporting plate in operative relation to said burner, a fireback on said supporting plate at the rear of said radiating elements, a front frame disposed on said panel around said opening, said frame having a hood at the top thereof and flanges at the top and sides thereof projecting through said opening, bolts arranged through said front frame and panel to engage the flanges on said casing and supporting plate, and a top for said casing, said casing being provided with a flue opening above said radiating elements.
2. A gas heater comprising a panel having an opening therein, a casing comprising sheet metal back and end walls having flanges at the front edges thereof disposed against the rear side of said panel at the edges of said opening therein, a supporting plate having a flange at its front end disposed within said casing and secured to the walls thereof, a burner mounted on said supporting plate, radiating elements disposed on said supporting plate in operative relation to said burner, a fireback on said supporting plate at the rear of said radiating elements, a front frame disposed on said panel around said opening, and bolts arranged through said front frame and panel to engage the flanges on said casing and supporting plate.
3. A gas heater comprising a panel having an opening therein, a casing comprising sheet metal back and end walls having flanges at the front edges thereof disposed against the rear side of said panel, a supporting plate disposed within said casing and secured to the walls thereof, a burner mounted on said supporting plate, radiating elements disposed on said supporting plate in operating relation to said burner, a fireback on said supporting plate at the rear of said radiating elements, a front frame disposed on said panel around said opening, and bolts arranged through said front frame and panel to engage the flanges on said casing and supporting plate.
4. A gas heater comprising a panel having an opening therein, a casing comprising sheet metal back and end walls having flanges at the front edges thereof disposed against the rear side of said panel, a supporting plate disposed within said casing and secured to the walls thereof, a burner mounted on said supporting plate, radiating elements disposed on said supporting plate in operating relation to said burner, a fireback on said supporting plate at the rear of said radiating elements, and means for securing said flanges to said panel.

5. A gas heater comprising a panel having an opening therein, a casing provided with a top and a vent opening, a supporting plate mounted within said casing, a burner mounted on said supporting plate, a radiating element disposed on said supporting plate in operative relation to said burner and in opposed relation to said opening, a front frame disposed on said panel around said opening, said frame having a flange at the top thereof of projecting through said opening, and bolts arranged through said front frame and panel to engage said casing.

6. A gas heater comprising a panel having an opening therein, a casing, a supporting plate mounted within said casing, a burner mounted on said supporting plate, a radiating element disposed on said supporting plate in operative relation to said burner and in opposed relation to said opening, a front frame disposed on said panel around said opening, and bolts arranged through said front frame and panel to engage said casing.

7. A gas heater comprising a supporting panel having an opening therein, a casing mounted on said supporting panel at the rear of said opening, a supporting plate mounted within said casing, a burner mounted on said supporting plate, and a radiating element disposed on said supporting plate in operative relation to said burner and in opposed relation to said opening.

8. A gas heater comprising a panel having an opening therein, a casing provided with a top and a vent opening, a burner, a radiating element operatively associated with said burner and disposed at the rear of said opening, a front frame disposed on said panel around said opening and having a forwardly projecting hood at the top thereof and a flange projecting through said opening, and supporting bolts for said casing arranged through said front frame and panel.

9. A gas heater comprising a panel having an opening therein, a casing, a burner, a radiating element operatively associated with said burner and disposed at the rear of said opening, a front frame disposed on said panel around said opening, and supporting bolts for said casing arranged through said front frame and panel.

10. A gas heater comprising a supporting panel having an opening therein, a casing mounted on the rear side of said panel, a supporting plate mounted within said casing, a burner mounted on said supporting plate, a radiating element disposed on said supporting plate in operative relation to said burner and opposed relation to said opening, and a fireback on said supporting plate at the rear of said radiating element.

11. A gas heater comprising a supporting panel having an opening therein, a casing mounted on the rear end of said panel, a heating unit of the radiant type within said cas-

ing in opposed relation to said opening, and a front frame mounted on said panel and disposed around said panel opening and provided with a forwardly projecting hood at the top and a flange projecting through said opening.

12. A gas heater comprising a supporting panel having an opening therein, a casing mounted on the rear side of said panel, a heating unit of the radiant type within said casing in opposed relation to said opening, and a front frame mounted on said panel and disposed around said panel opening and a flange projecting through said opening.
15. 13. A gas heater comprising a supporting panel having an opening therein, a casing mounted on the rear side of said panel, a heating unit of the radiant type within said casing in opposed relation to said opening, and a front frame mounted on said panel and disposed around said panel opening and pro-
- 20

vided with a forwardly projecting hood at the top.

14. A gas heater comprising a supporting panel having an opening therein, a heating unit of the radiant type mounted on the rear side of said panel with its radiating element in opposed relation to said opening therein, and a front frame on said panel provided with a forwardly projecting hood at the top thereof and an inwardly projecting flange at the top projecting through said opening.

15. A gas heater comprising a supporting panel having an opening therein, and a heating unit of the radiant type mounted on the rear of and entirely supported by said panel with its radiating element in opposed relation to said opening therein.

In witness whereof I have hereunto set my hand.

GEORGE A. HUMPHREY.
